LOOM

William Henry Baker, Montreal, Quebec,
Canada

Application April 15, 1935, Serial No. 16,423

4 Claims. (Cl. 139—279)

This invention relates to improvements designed to increase the efficiency of looms, more especially automatic looms that have been equipped with shifting shuttle boxes, as described in my application for Letters Patent Serial #652343. The invention pertains to an improved feeler mechanism designed to operate successfully with all grades of filling yarns whether spun directly on loom bobbins, or rewound on special bobbins after the spinning operation.

My invention further relates to arrangements, and combinations of parts which are hereinafter described, and more particularly pointed out in the claims.

15 In the accompanying drawings;

Fig. 1 is a front general view of the new filling feeler mounted in place on the back of the lay.

Fig. 2 is a side view of Fig. 1.

Fig. 3 is a fragmentary view of the filling feeler 20 contacting a full bobbin.

Fig. 4 is like Fig. 3 with the feeler contacting a depleted bobbin.

Fig. 5 is a plan view of the feeler indicating mechanism mounted on the breast beam of the 25 loom.

Fig. 6 is a front elevation of Fig. 5.

Fig. 7 is a fragmentary sectional view showing the train of actuator levers.

Fig. 8 is a fragmentary view like Fig. 7 with 30 the indicator parts enlarged in the normal or running position.

Fig. 9 is like Fig. 8 showing the indicating parts in the abnormal or indicating position.

Fig. 10 is a cross section of the latch finger 35 elevating mechanism taken on line B—B Fig. 9.

The new filling feeler described and shown in the accompanying drawings is of the penetrating type. The indication is actuated when the penetrating point contacts the relatively hard surface of the bobbin through the last few convolutions of yarn on the bobbin when the filling is exhausted to a predetermined extent. This feeler can be used in any position desired with suitable arrangements to utilize the feeling 40 action, and the various elements of the mechanism can be changed without departing from the spirit of the invention, but a preferred form is here shown and described. An important feature of this invention is a feeler of this class 45 mounted vertically, and entirely mechanically operated. Another feature is the use of a penetrating feeler on the moving lay. Still another feature is the swinging hood or protector to prevent the penetrating member from contacting 50 the yarn, the bobbin or the metal rings on the

bobbin or any exposed parts of the shuttle when the same is improperly boxed, until the yarn is nearly spent or run out. Another feature is the lateral swinging of a mechanical feeler on its support to prevent the penetrating point from 5 cutting the filling on the bobbin, if and when the shuttle is moved a short distance endwise under the influence of the picker and box guide when the box motion operates to shift the shuttle boxes, and a spring to replace the feeler after the 10 box motion has moved the shuttle and filling bobbin away from contact with the feeler.

In the drawings Figs. 1 and 2, 14 is the back of the lay on a loom fitted with shifting shuttle box motions, as described. 60 is a bracket or 15 mounting for the feeler attached thereto at one extremity, and having another bracket 61 with a bearing 62 at the other extremity, in which the fulcrumed bed or base 63 of the feeler is fitted. A projection or journal 64 20 on the bed turns in the fulcrum, and is held in position by the nuts and lock washer 65, all shown clearly in Fig. 2. On the bracket 61 resides a suitable spring socket 65A within which is a chamber 66 for the spring 67 and a plunger 25 68 mounted to transmit the urge of the spring 67 to the feeler base 63 to replace the feeler to the normal position against the adjusting screw stop 69, if the feeler has been turned on the journal 64 by movement endwise of the shuttle 30 and bobbin in the shuttle box with the feeler point imbedded in the filling at the time that the boxes change. The frame 70 of the feeler is fastened to the bed 63 by a bolt 71 through adjusting slots 35 in the feeler for adjustment toward and away from the bobbin in the shuttle. In the feeler frame 70 slides the movable part or body of the feeler 72. This body is adapted to slide in the guides 73 and 74. The guide 73 is made integral with the feeler frame 70, but the guide 74 can be 40 adjusted for wear as shown, and is held in position by the screws 75 and 76. The round extension on the body 72 shown as 77 forms a holder for the main spring 78 Figs. 1 and 2, and passes through the extension 79 on the guide 74, as an 45 additional guide and support to the feeler body. This spring 78 provides the necessary tension to press the parts against the filling during the process of feeling. At one extremity of the body 72 is a smooth surface 80 to contact the filling on 50 the bobbin, having a longitudinal hole 81, drilled to receive the penetrating member which projects from this surface in the form of a point, or other desired form 82, and contacts the filling 83 on the bobbin 84 as shown in Figs. 2 and 3. 55

As long as there is sufficient filling on the bobbin, as shown in Figs. 2 and 3 no indicating movement is derived from the feeler, but when the bobbin is denuded to a predetermined extent as shown in Fig. 4 the spur of the penetrating member or point 82 comes in contact with the hard surface of the bobbin through the last few convolutions of the filling on the bobbin and the indicating movement is produced. The opposite 10 end of the penetrating member 82 is offset as at 85, and impinges on an adjusting screw 86 threaded into the small lever 87 which is hinged at 88 in the feeler body 72, and extends through to the opposite side where it has a boss 89, into 15 which is fastened the striker pin 90. The stop 91 is made integral with the movable feeler body 72 which limits the movement of the lever 87 under the urge of the spring 93. Projecting from one side of the lever 87 is a small projection 102 20 and a socket 92 is formed on the feeler body 72 to receive the light spring 93 which serves to keep the parts just described in normal position with the point of the penetrating member 82 protruding from the surface 80 for feeling purposes. The 25 striker plate 94 on the post 95 is described elsewhere in this specification. The protector 96 is fulcrumed on the common bolt 88 in the body 72 and so formed to fit around the feeler end 80 to permit a small lateral swinging movement to 30 enable the protector to move laterally a short distance either way thereby accommodating it self to the slight variations in the different bobbins. To prevent the protector from swinging too freely back and forth as the loom runs, a hole 35 97 Fig. 1 is formed in the feeler body 72 and projections or ears 98 are formed on the protector 96 with parallel surfaces facing inward, and a spring 99 and two balls 100, one on each end of the spring in the hole, are pressed by the spring 99 against the inside of the ears 98 Fig. 2 to cause 40 a slight friction, and the excessive wear due to free swinging of the protector as the loom runs is prevented.

In the preferred form shown this feeler is mounted on the back of the lay 14 above the 45 shifting shuttle box and adjusted so that the feeler protector 96 will be pressed against the bobbin by the action of the main spring 78 until the yarn is nearly exhausted and thereafter the main feeler body surface 80 will contact the bobbin 50 for a few picks, and the penetrating member 82 will enter between the yielding convolutions of the filling 83 on the bobbin 84 and any additional movement of the shuttle and bobbin toward the 55 feeler will be compensated for by the main spring 78. Should the picker be worn, or for any other cause the shuttle move endwise in the shuttle box after it has arrived, the filling would produce a lateral pressure on the penetration part of the feeler 82 and the whole feeler mass with the bed would turn on the journal 64 causing the feeler to move laterally to a position indicated by the dotted lines 101 Fig. 1. After the shuttle box operating mechanism has moved the shuttle and filling bobbin therein away from the 60 feeler, the spring 67 and the plunger 68 will move the feeler mass back to the normal position against the adjusting screw stop 69. If there was plenty of filling on the bobbin during this 65 operation of the feeler, no indication would be made, but if the filling was exhausted to a predetermined extent as indicated in Fig. 4, then the penetrating point 82 would contact the hard surface of the bobbin through the remaining convolutions of filling, and this resistance would 70

overcome the spring 93 through the screw 86 and the lever 87 and the striker pin 90 will be moved to strike the striker plate 94 on the post 95, thereby actuating the filling replenishing instrumentalities when the lay passes the front center. 5

Another important feature of the invention is the feeler indication transmitter, adapted to take up the indicating movement received from the filling feeler and transmit the same to the filling changing instrumentalities at the opposite side 10 of the loom.

This takes the form of a housing 105 bolted to a bracket 106 on the feeler side of the loom Figs. 5, 6, 7, 8, 9 and 10. Mounted in bearings in this housing 105 is a shaft 95 with the striker plate 15 94 at the top, and the small lever 107 fastened to same and extending through the slot 108 in the housing to guide and limit the movement of lever 107. Attached to the lever 107 is a forked shackle 108a in which is threaded, or otherwise 20 held, a small rod 109 which extends to the latch finger lifting device. This lifter is composed of a base 110 bolted to the bracket 106. Into this base is screwed the guide or fulcrum tube 111 Fig. 9, and surrounding this tube is the movable member 112. This movable member has an inclined surface 113 which fits against a similar surface 114 on the base 110 Figs. 8 and 9. The movable member has an arm 115, shown clearly in Fig. 5 to which is attached one end of the connecting 30 rod 109, by which the movable member 112 is moved to cause the inclined plane on same to slide up the inclined plane 114 on the base 110 Fig. 8, to elevate the movable member when feeler indication is affected. The spring 116 within the 35 tube is held at the bottom by a cross pin 117 in the cavity 118 in the base 110 provided for it, and at the top by a pin 117a in the specially formed collar or cap 119 Figs. 6 and 10 which fits over the end of the tube 111 to hold the spring 40 under tension. It is the function of this spring to hold the two main parts of this elevating device together yieldingly and permit their separation when the movable member is elevated by the inclines. On this movable member is a shelf 45 122 shown clearly in Figs. 5 and 10. Attached to the upright arm 124 Fig. 7 mounted on the cross shaft 125 used to call a bobbin change from the filling changing instrumentalities at the opposite side of the loom (see my United States application hereinbefore referred to) is a latch finger 123. This latch finger 123 is operated by a train of levers, now to be described. Fig. 7 shows this movement originating with the cam 29, the cam follower 39, and the actuator lever 38. This lever is fulcrumed on the loom frame at 126, with the upward extension 127, all of which with the exception of the composite cam unit is described in the above application referred to. There is a knife edged pin or driver 128 shown clearly in Figs. 7, 8 and 9, adapted to contact the latch finger 123 when same is elevated by a feeler actuation. On the side of the latch finger 123 is mounted a small latch or ratchet pawl 129, shown clearly in Figs. 8 and 9. In Fig. 8 this is shown in the normal position with actuator 127 in its full backward stroke. Fig. 9 shows the latch finger raised into operating position with the actuator in its full forward position, showing the relation of the pawl 129 to the shelf 122 on the 55 movable member 112. In this figure it will be noted that this pawl has slid back over the shelf 122, and dropped down behind same, where it will strike against the edge of the shelf on the return stroke of the actuator 127 pushing 60

the movable member 112 off the top of the incline 114 Fig. 9 thereby replacing all the parts to normal position to await another feeler indication.

5 The operation of this device is as follows: When a bobbin in a running shuttle has been exhausted to a predetermined extent, the feeler indicates a change. On the next forward beat of the lay, the striker pin 90, on the feeler, strikes 10 the striker plate 94 on the shaft 95. This rotates the shaft slightly, moving the lever 107 set 15 screwed fast to it. Through the shackle 108A the connecting rod 109 is pushed endwise, and the movable member will be turned on its fulcrum causing the part to rise due to the incline or cam surfaces 113 and 114. This movement causes the shelf 122 to raise the latch finger 123 and the parts just described are held quiescent in this position until the actuator again moves 20 forward, when the latch finger will be moved with it, and the cross shaft 125 through the arm 124 will be rotated to call a bobbin change. As the actuator again moves backward the pawl 129 will 25 push the shelf 122 on the movable member 112 off the top of the incline, and the parts including the striker plate 94 will be returned to normal position to await another cycle of automatic filling replenishment.

Having thus described my invention, what I 30 claim is:

1. In a lay mounted filling feeler in combination, a sliding body normally maintained in filling contacting position, a penetrating member for said body, a filling contacting protector pivoted to said body provided with a slot through 35 which the penetrating member extends, said protector being vibratable transversely of the lay with respect to its pivot and upon filling contact, and means residing in the sliding body in con-

tact with said protector whereby free vibration of the protector is prevented due to influence of the moving lay.

2. In an automatic loom, a lay, a filling feeler mounted on the lay, a sliding body therefor normally maintained in filling contacting position, a penetrating member for said body, an operatively related striker pin pivoted to said body to be actuated upon detection of filling exhaustion by said member, a striker 5 plate on the loom to be actuated by said pin on the forward beat of the lay after detection of filling exhaustion by the aforesaid member, a latch finger and an actuator, and controlling means connected to said plate to move the latch 10 finger into the path of the actuator when the pin strikes the plate.

3. In a loom, a filling feeler, means to support it on the lay including a bracket provided with a stop, a laterally displaceable feeler carrying 20 frame pivoted thereto and normally located against the stop, and yielding means associating said bracket with the frame to replace said frame against the stop in the vent of lateral displacement of said frame.

4. In a loom, a lay, a filling feeler mounted on the lay, a sliding body therefor normally maintained in filling contacting position, filling exhaustion indicating means associated with said body, an additional filling contacting element 30 pivoted to said body to project substantially beyond said means, said element being vibratable with respect to said body upon filling contact and restraining means including friction members associating said element with the body whereby free 35 vibration of said element is prevented due to influence of the moving lay.

WILLIAM HENRY BAKER.
